(57) CLAIM

The ornamental design for the bamboo napkin holder, as shown and described.

DESCRIPTION

FIG. 1 is a right perspective view of a bamboo napkin holder showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

FIG. 8 is a right perspective view of a bamboo napkin holder showing our new design in accordance with another embodiment;

FIG. 9 is a front view thereof;

FIG. 10 is a rear view thereof;

FIG. 11 is a top plan view thereof;

FIG. 12 is a bottom plan view thereof;

FIG. 13 is a left side view thereof; and,

FIG. 14 is a right side view thereof.

Stippling is used in FIGS. 8 to 14 to illustrate a contrast in materials, textures, colors and/or finishes for different areas of the new design.
